UNITED STATES PATENT OFFICE

146,099

DESIGN FOR A TURNING SIGNAL

Charles E. Edwards, Santa Paula, Calif.

Application December 18, 1945, Serial No. 124,820

Term of patent 7 years

(Cl. D72—1)

To all whom it may concern:

Be it known that I, Charles E. Edwards, a citizen of the United States, residing at Santa Paula, in the county of Ventura and State of California, have invented a new, original, and ornamental Design for a Turning Signal, of which the following is a specification, reference being had to the accompanying drawing, forming part thereof.

Figure 1 is a side elevation showing my new design for a turning signal.

Figure 2 is a front elevation.

Figure 3 is a rear elevation.

Figure 4 is a top view.

I claim:

The ornamental design for a turning signal, as shown.

CHARLES E. EDWARDS.
